UNITED STATES PATENT OFFICE.

CONRAD ALLES, OF PECK, IDAHO.

AX.

1,322,993.

Specification of Letters Patent. Patented Nov. 25, 1919.

Application filed April 12, 1919. Serial No. 289,523.

To all whom it may concern:

Be it known that I, CONRAD ALLES, a citizen of the United States, residing at Peck, in the county of Nez Perces and State of Idaho, have invented certain new and useful Improvements in Axes, of which the following is a specification, reference being had to the accompanying drawings.

This invention relates to the art of cutting tools, particularly those of the chopping kind, and more especially to an ax, and the invention in its broadest aspect aims to provide improved means for detachably and firmly connecting the ax-head to the handle. The invention further aims to provide an ax, so constructed as to prevent the ax from becoming detached, when being in use, that is intermittently swinging over the wood chopper or other operator's head. In fact, this particular means for preventing detachment of the ax from the handle is rendered more and more secure while the ax is being constantly used, for the reason that owing to the centrifugal force, the ax-head binds closer in contact with the handle, the more the ax is used.

The invention further aims to provide an ax having a cutting blade, and a head portion, one face of which is recessed for the reception of the outer extremity of the ax handle, said recess having upper and lower converging walls, which will insure constant binding of the ax handle between the walls, the more the ax is used, that is swingingly in the operator's hands.

The invention further aims to provide a cover plate, to cover the recessed face of the head of the ax, to retain the outer end of the handle in said recess, there being a tongue and groove connection for the lower part of the cover plate, means for detachably connecting the upper flange of said plate, and the flange or wall of the upper part of the recess, said flanges or walls overlapping, and means for detachably connecting said flanges. It is obvious that when the means such as set bolts or the like are removed, the cover plate may be easily disconnected, and the ax handle removed.

The invention further aims to provide tongue and groove connections, longitudinally and transversely of the overlapping flanges, thereby rendering them more secure and rigid relative to each other.

While the design and construction at present illustrated and set forth is deemed

preferable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings and claimed.

In the drawings:

Figure 1 is a view in perspective of the ax constructed in accordance with the invention and applied to the ax handle.

Fig. 2 is a vertical sectional view on line 2-2 of Fig. 1, that is transversely thereof.

Fig. 3 is a vertical sectional view on line 3-3 of Fig. 2, showing the inclined or converging walls of the recess for the ax handle.

Fig. 4 is a detail perspective view of the cover plate.

Referring more especially to the drawings 1 designates the head of an ax, provided with the usual cutting blade 2, provided with a cutting edge 3. The head of the ax has a transverse recess 4. It is to be noted that this recess is tapered, in other words, the upper and lower walls thereof converge, in a direction toward the hand grasping portion of the handle, whereby the outer end of the handle will frictionally bind in the recess owing to the centrifugal action due to swinging the ax over the head. Adjoining the lower wall 6 of the recess, the face of the blade, that is at a point immediately between the blade and the head of the ax being provided with an L-shaped groove 7. This groove is bound on one side by a rib 8, which is disposed over a flange 9. The upper wall 10 of the recess is in the form of a flange forming an integral part of the head of the ax. The upper face of this flange or wall 10 has a transverse groove 11. The flange 10 in cross-section is of a shape to conform to and engage one edge of the ax handle, whereby the ax handle may fit the recess snugly. A suitable cover plate 12 is provided. The lower part of this cover plate has an L-shaped flange or portion 13, which engages the L-shaped groove 7, the rib 8 and the flange 9 engaging in close position to the transverse part of the L-shaped tongue 13, thereby so retaining the flange in the L-shaped groove,

when the cover plate is in contact with the ax head, but permitting the cover plate to be moved, or swung slightly outwardly, so as to permit of its detachment from the head 5 of the ax. The upper part of the cover plate has a laterally extending flange 14, its connection with the cover plate being integral. This flange 14 overlies the flange or wall 10, and is provided on its underface 10 with a transverse rib 15 to engage the transverse groove or recess 11. The provision of this transverse tongue 15 in engagement with the groove 11 prevents a sliding movement of the cover plate, but the securing 15 means is passed through the flange. Even after the securing means is arranged in the flange 14, the tongue and groove 15 and 11 reinforce the flange 14 in position. It is to be noted that one edge of the wall or 20 flange 10 is beveled as shown at 16, in order to engage the beveled surface 17, at the point where the flange 14 integrally unites to the cover plate. Adjacent to but slightly spaced from the beveled surface 17 is a rib 18, forming 25 an integral part of the inner face of the cover plate. This rib 18 is provided with a bevel 19, to engage the beveled part 20 of the ax handle, and the upper face of this rib is at right angles to the inner surface 30 of the cover plate, so as to engage the under surface of the flange 10. By the provision of this rib it is to be noted that the flange or wall 10, when the cover plate is in position engages between this rib and the 35 bevel 17, thereby rendering the connection of the cover plate and the flange 10 more secure. Suitable set bolts 21 are threaded through the flange 14 and flange 10, thereby 40 securely connecting the cover plate in position. It is obvious that by the removal of the set bolts, the cover plate may be swung slightly laterally, disengaging the tongue 15 from the transverse groove or recess 11, after which the L-shaped tongue 45 13 may be easily disconnected from the L-shaped groove 7, after which the ax handle may be easily removed from the recess of the ax head.

The invention having been set forth, what 50 is claimed as new and useful is:

1. The combination with an ax blade in-

cluding a head, which is provided with a transversely disposed recess having a lower wall, the upper part of the head having a flange, said flange and the wall being convergent, of an ax handle engaging in said recess between the convergent wall and flange, a cover plate for the recess, the lower part of the cover plate having detachable connections with the ax blade, the upper 60 part of the cover plate having a lateral flange overlying the first flange, the upper part of the cover plate at a point where the latter flange integrally connects to the cover plate being provided with a groove 65 for the reception of the former flange, said overlapping flanges having a transverse tongue and groove connection, and means for connecting the flanges together.

2. The combination with an ax blade including a head provided with a transversely disposed recess, the lower wall of which being inclined longitudinally, said head immediately below the lower inclined wall of the recess on one face thereof provided 75 with a transverse groove angular in cross section, of a handle having its tapered end engaging the transversely disposed recess, a cover plate having a flange at its lower portion, angular in cross section corresponding 80 to and fitting the groove, said cover plate overlying the handle and provided with a rib engaged between a portion of the handle and the upper wall of the recess, the upper extreme edge portion of the cover plate having 85 a flange extending at right angles to the plate and overlying the upper wall of the recess, a tongue and groove connection between the flange and the upper wall of the recess extending transversely thereof, and 90 fastening screws passing through the transversely disposed flange and the upper wall of the recess thereby holding the parts together and providing outward movement of the cover plate.

In testimony whereof I hereunto affix my signature in the presence of two witnesses.

CONRAD ALLES.
